UNITED STATES PATENT OFFICE.

JOHN D. COMPTON, OF MINNEAPOLIS, MINNESOTA.

VALVE-LOCK.

1,287,641.

Specification of Letters Patent. Patented Dec. 17, 1918.

Application filed May 19, 1916. Serial No. 98,568.

To all whom it may concern:

Be it known that I, JOHN D. COMPTON, a citizen of the United States, residing at Minneapolis, in the county of Hennepin and 5 State of Minnesota, have invented certain new and useful Improvements in Valve-Locks, of which the following is a specification.

My invention relates to valve locks and 10 has for an object to provide a lock by which the flow of fluid in a pipe-line may be shut off by simply turning the key in the lock. In carrying out my invention I provide a lock having a pair of ports which pass 15 through the lock body and which communicate with the interior of a casing attached thereto. A valve head is eccentrically secured to the lock barrel, being seated on the lock body covering said ports and is adapt- 20 ed to open the ports as the barrel is rotated, permitting the fluid to flow from one port to the other through the casing.

The full objects and advantages of my invention will appear in connection with the 25 detailed description thereof and are particularly pointed out in the claims.

In the drawings, illustrating the application of my invention in one form,—

Figure 1 is a front elevational view of my 30 invention with parts cut away and parts drawn in section. Fig. 2 is an elevational sectional view taken on line 2—2 of Fig. 1. Fig. 3 is a plan sectional view taken substantially on line 3—3 of Fig. 1. Fig. 4 is an elevational sectional view taken on line 4—4 of Fig. 3. Fig. 5 is a view similar to Fig. 4 with the valve head removed.

In constructing my invention I employ 40 the usual barrel lock 10, which is clearly shown in Figs. 1, 2 and 3. A body portion 11 is formed with a tumbler housing 12 and a barrel housing 13 in which is mounted a barrel 14 in the usual manner. These 45 housings are cast integral with each other and with a flanged facing plate 15 through which the barrel 14 projects. The whole body of the lock is externally threaded, as clearly shown in Fig. 3.

The manner of applying the lock proper 50 to the pipe-line will now be described. A casing 16 having a cylindrical portion 17 is internally threaded to receive the threaded body 11 of the lock 10, which is screwed into said casing up to the flange of the 55 plate 15 and securely held in place by a set-screw 18, which when sealed will prevent

removing the lock barrel as best shown in Fig. 2. The lock may be pressed into this cylinder if desired, thus permanently securing it in place. The cylindrical portion 17 60 of casing 16 extends throughout the whole length of the lock body 11 and forms with the portions 12 and 13 thereof two chambers 19 and 20, as best shown in Figs. 1 and 3. A pair of pipe connections 21 and 22 are 65 screwed into bosses 23 and 24 formed on opposite sides of casing 17 and serve to connect the pipe-line 25—26 with the chambers 19 and 20 previously mentioned. These chambers communicate with a discoidal 70 chamber 27 formed on the rear of the casing 16 by a portion 28 of said casing through two ports 29 and 30 drilled through the body 11 of the lock 10.

The valve head and seat are constructed 75 as follows, and are best shown in Figs. 2, 3, 4 and 5. A discoidal valve head 31 of a diameter equal to that of the lock body 11 is ground on one surface and is adapted to be seated upon the rear end of said lock 80 body 11, which surface is similarly ground. The major portion of the rear of the barrel 14 falls below the surface 32 of the lock body and is provided with a rectangular lug 33 projecting rearwardly of the lock 85 body, which lug has attached to it at one end a long threaded spindle 34. Valve head 31 is provided with a rectangular cavity 35 into which the lug 33 may extend and is held firmly seated on the lock body 11 by 90 means of a crowfoot spring 36 mounted on the spindle 34 under a lock nut 37. The cavity 35 in said valve head is somewhat deeper than the lug 33 so that said head will always remain seated regardless of the wear 95 of the valve surfaces.

The operation of the valve can best be comprehended from Fig. 4. When the lock barrel is rotated so the lock is closed the same is positioned as shown in Fig. 1 and 100 105 the valve head 31 covers both ports 29 and 30, as shown in full lines in Fig. 4. When the lock is opened the valve head is rotated one hundred and eighty degrees and takes the position shown in dotted lines in Fig. 4, 105 uncovering both of said ports. When in this position the fluid in the pipe line flows freely from one of these ports to the other through the chamber 27. To prevent the fluid from escaping into the lock mechanism 110 110 a tapered packing washer 38 is interposed between the valve head 31 and the lug 33

on the spindle 34. In this manner the joint between the barrel 14 and the valve head 31 is rendered non-leakable. It will be noted that the chamber 27 is somewhat enlarged in 5 diameter as compared to the lock casing 16, providing operating space for the valve disk 31, which as shown in Fig. 4 in dotted lines extends somewhat beyond the edge of the body proper.

10 In order to tap the pipe-line a pet cock 39 may be screwed into the bottom of the casing 28. This is of special value when the valve lock is used in conjunction with automobile feed lines where it is sometimes desirable to secure a portion of the fuel for 15 priming purposes.

The lock may be conveniently mounted to 20 protrude through an instrument board 40, or similar device, as clearly shown in Figs. 2 and 3. For this purpose a pair of brackets 41 are formed integral with the lock housing 16 through which suitable screws may be inserted to hold the device in place.

25 The advantages of my invention are manifest. The device can be easily made and occupies very little space. The valve is mounted directly on the lock proper and may be removed therewith. No levers or handles are required as the lock barrel is directly 30 secured to the valve head and the same is hence rotated by means of the barrel through the key. There are no exposed parts to be tampered with and the valve cannot be operated without the key to cause 35 the fluid to flow. With the form of lock employed the key remains in the key-way when the lock is open. This is especially advantageous for use with automobiles, as dirt cannot enter and clog the key-way when the 40 vehicle is in operation.

I claim:

1. A valve locking device comprising a

casing, a barrel lock having a body portion mounted in said casing and provided with separated chambers, said chambers being 45 severally in communication with a pipe line, a separate chamber formed within the casing having ports communicating with the first named chambers and a valve member connected with the barrel of said lock and 50 operated thereby to cover and uncover said ports.

2. A valve locking device comprising a casing, a barrel lock having a body portion mounted in said casing and provided with 55 separated chambers, said chambers being severally in communication with a pipe line, a separate chamber formed within the casing having ports communicating with the first named chambers, a valve plate rigidly 60 connected with the barrel of said lock and having a portion offset therefrom and eccentrically rotatable therewith to cover and uncover said ports when the lock is operated.

65 3. A valve locking device comprising a casing, a barrel lock having a body portion mounted in said casing and provided with separated chambers, said chambers being severally in communication with a pipe line, 70 a separate chamber formed within the casing having ports communicating with the first named chambers, and a discoidal valve head operating within said separate chamber and secured to and operated by said 75 barrel for opening and closing communication of said ports with the separate chamber.

In testimony whereof I affix my signature in presence of two witnesses.

JOHN D. COMPTON.
